LOOPED PILE CARPET OR SIMILAR ARTICLE

George V. Uihlein, Worcester, Mass., assignor to M. J.
Whittall Associates, Inc., Worcester, Mass.

Application July 9, 1954, Serial No. 31,365

Term of patent 7 years

(Cl. D92—4)

The figure on the drawing is a plan view of a looped pile carpet showing my new design. The dot and dash lines on the drawing outline a design unit, which unit is repeated in regular succession as indicated by the extensions beyond the unit boundaries.

I claim:

The ornamental design for a looped pile carpet or similar article, substantially as shown and described.
